DESIGN FOR A COMBINATION ELECTRIC TOASTER AND COOKER OR SIMILAR ARTICLE

Daniel Platkin, Los Angeles, Calif.

Application June 11, 1945, Serial No. 120,005

Term of patent 14 years

(Cl. D81—10)

To all whom it may concern:

Be it known that I, Daniel Platkin, a citizen of the United States, residing in the city of Los Angeles, in the county of Los Angeles, State of California, have invented a new, original, and ornamental Design for Combination Electric Toaster and Cooker or Similar Article, of which the following is a specification, reference being had to the accompanying drawing, forming a part thereof.

The figure is a perspective view of the combina-

tion electric toaster and cooker showing my new design.

The other side and end, not shown, are substantially plain except for the continuous horizontal lines spaced from the top and bottom, respectively, as shown.

I claim:

The ornamental design for a combination electric toaster and cooker or similar article, as shown and described.

DANIEL PLATKIN.
